ATTORNEY

UNITED STATES PATENT OFFICE.

LOUIS SANDERS, OF NEW YORK, N. Y.

FAN.

SPECIFICATION forming part of Letters Patent No. 237,606, dated February 8, 1881.

Application filed December 15, 1880. (No model.)

To all whom it may concern:

Be it known that I, LOUIS SANDERS, of the city, county, and State of New York, have invented certain new and useful Improvements 5 in Fans, of which the following is a specification.

This invention has reference to improvements in that class of fans in which the frame is centrally split into two sections and one handle-section pivoted at the upper end to the other section, so as to be swung on the pivot through an entire circle, and cause thereby the opening or closing of the web of the fan.

The invention consists of two longitudinally-divided handle-sections, which are pivoted to each other at their upper ends, and connected to the web by sidewise-extending pins or studs of the end strips of the web, said pins engaging transverse guide slots or grooves 20 of the upper wider parts of the handle-sections.

In the accompanying drawings, Figure 1 represents a side elevation of my improved fan, shown as partly open. Fig. 2 is an end view of the same, partly in section; and Fig. 25 3, a horizontal section on line x x , Fig. 2.

Similar letters of reference indicate corresponding parts.

Referring to the drawings, A represents the web, and B B the handle-sections, of my improved fan. The handle-sections are wider at their upper parts, where they inclose the web, and of narrower semicircular shape at their lower parts, so as to form the handle proper when placed one above the other. The handle-sections are longitudinally divided and pivoted to each other at their upper ends and centrally to the web. The end folds of the web A are applied to strips C, which are arranged at their outer ends with pins or studs 35 a , which extend in opposite directions to each other into transverse guide-slots or interior grooves, b , of the handle-sections B, as shown clearly in Fig. 3. The end strips, C, of the web

may thereby move in the space between the upper wider parts of the handle-sections from 45 one side to the other as far as the slots will allow, so that when one handle-section is swung on its pivot through an entire circle for opening or closing the fan, the end strips change at the same time their position. The guiding of 50 the end strips by means of their pins in the slots or grooves of the handle-sections forms a reliable and durable connection of the web and handles. When the handle-section has been swung through a circle, as desired, 55 whether for opening or closing the fan, its lower end is secured to the other handle-section by an axially-turning socket, D, which is applied to the lower end of the other handle-section. The cap or socket D has a recess, d , 60 of sufficient size to admit the entrance of the lower end of the swinging handle-section, after which the socket is turned around its axis, so as to lock thereby the swinging handle-section reliably to the other section and retain the 65 fan in open or closed position.

Having thus described my invention, I claim as new and desire to secure by Letters Patent—

As an improvement in fans, the combination 70 of pivoted handle-sections B B, provided with transverse guide slots or grooves, with web A, having end strips, C, and pins or studs $a a$, which extend in opposite directions to each other into the guide slots or grooves of the handle-sections, substantially as and for the purpose set forth.

In testimony that I claim the foregoing as my invention I have signed my name, in presence of two witnesses, this 13th day of December, 1880.

LOUIS SANDERS.
